UNITED STATES PATENT OFFICE.

FAY HARRY ROSENCRANTS, OF KINGSWAY, LONDON, ENGLAND, ASSIGNOR TO INTERNATIONAL COMBUSTION, LIMITED, OF LONDON, ENGLAND.

APPARATUS FOR DRYING GRANULAR MATERIAL.

Application filed October 15, 1924. Serial No. 743,723.

To all whom it may concern:

Be it known that I, FAY HARRY ROSENCRANTS, a citizen of the United States of America, residing at Kingsway, London, 5 W. C. 2, England, have invented a certain new and useful Improved Apparatus for Drying Granular Material; and I do hereby declare the following to be a full, clear, and exact description of the invention, such 10 as will enable others skilled in the art to which it appertains to make and use the same.

This invention has for its object to provide an improved apparatus for drying slack, or crushed coal or other fuel, and other more or less granular materials.

While primarily intended for use in drying slack, crushed or fine coal or fuel preparatory to pulverizing the same for use in the 20 furnaces of steam generators and in other furnaces, the method and apparatus according to this invention might be employed for drying other materials including powdered, pulverized or granular substances or materials.

As is known coal and other fuels contain moisture, and the percentage of moisture varies in different classes or grades of fuel, and it is also well known that a fuel or other 30 granular material must not contain more than a very limited amount of moisture to permit of its being pulverized in a successful and economical manner. The methods and apparatus heretofore proposed or employed for drying fuel by means of hot gas or air while capable of dealing with fuel containing say 8 to 10 per cent of moisture are not suitable for dealing effectively with fuel containing higher percentages of moisture. It is the principal object of this 40 invention to provide a method and apparatus whereby fuel or other granular material containing high percentages of moisture can be effectively and properly dried, the said 45 method and apparatus being furthermore capable of drying coarse to the most finely divided fuel or other material in a rapid and economical manner.

The apparatus for drying fuel (or powdered or granular material) according to this invention contemplates and embraces a plurality of plates, trays or the like carried by a frame, casing or structure to which motion in the desired direction can be given, several of the desired number of sets or series

of such plates or trays being provided and arranged in such a manner that the material delivered on to the plates or trays of the first set and partially dried by the action of the apparatus is at the required time or times 60 automatically removed from the said plates or trays of the first set or series and transferred or permitted to drop on to the plates or trays of the next set or series, and so on from one set or series of plates or trays to 65 the next until the complete drying operation has been effected, this transferring of the material from the trays or plates of one set to the trays or plates of the next set being effected by means of mechanical scraping 70 devices past which the trays move during the drying process or operation. Furthermore, a mechanical spreader or spreaders is or are provided for each set or series of plates or trays whereby the fuel or material 75 delivered in a heap on to a plate or tray is nicely spread in a relatively thin layer on the surface of the plate or tray by means of the mechanical spreader as the tray is moving past the said spreader. When the trays 80 with the material spread thereon have been given the predetermined movement or traverse in the casing or drying chamber (to which gases of combustion, hot air, or other medium is admitted, primarily for the purpose of carrying away moisture and it may be also heating the coal), for instance when each tray of the first set is approaching the inlet for the material to be dried, one of the aforesaid mechanical scrapers will automatically act to scrape the material off the tray 85 so that it falls therefrom on to one of the trays of the next or lower set, the trays in adjacent sets being preferably arranged in staggered relation so that the material can 90 drop from a tray of one set through the space between the adjacent trays of the said set on to a tray of the next or lower set.

Fig. 1 of the accompanying illustrative drawings shows in central vertical section a 100 construction of apparatus embodying the invention, suitable for the drying of slack or crushed coal.

Fig. 2 is a plan of the apparatus.

Fig. 3 is a horizontal section corresponding to the line A—A of Fig. 1.

Fig. 4 shows the rotary feeding device in end elevation.

Fig. 5 is an elevation of the lower or discharge end of the apparatus.

Fig. 6 is a horizontal section corresponding to the line B—B of Fig. 1.

Fig. 7 is a developed view showing some of the carrier plates and steam connections thereto.

Fig. 8 is a detail view to a larger scale of the steam and drain pipe connections to the carrier plates.

Fig. 9 is an end elevation of one of the carrier plates.

Fig. 10 is a section corresponding to the line C—C of Fig. 11.

Fig. 11 shows one of the carrier plates in plan.

Fig. 12 is a similar view to Fig. 11 illustrating a modified construction of carrier plate.

Fig. 13 is a section corresponding to the line D—D of Fig. 12.

Fig. 14 is a similar view to Fig. 8 showing the steam and drain pipe connections to the modified construction of carrier plates.

Fig. 15 is a vertical sectional elevation of the upper end of the drying apparatus illustrating a modification.

Fig. 16 is a horizontal section corresponding to the line E—E of Fig. 15.

Fig. 17 is a developed view showing the modified feeding device illustrated in Figs. 15 and 16.

Fig. 18 is a side elevation and Fig. 19 a plan of one of the perforated rocking plates of the modified feeding device.

Fig. 20 is a section corresponding to the line F—F of Fig. 19.

The drying apparatus illustrated comprises a plurality of carrier plates 1 arranged in annular rows and secured at their inner ends, as by bolts, to the outer circumference of a rotatable drum 2 mounted within a suitable fixed drum or casing 3.

The carrier plates are arranged in annular rows about the circumference of the rotary drum, there being any desired number of plates in each row, (ten in the example illustrated), and any desired number of these annular rows of plates being arranged one row above the other in staggered relation and the said rows are suitably spaced apart in the vertical direction with the plates of each row also suitably spaced apart in the lateral or circumferential direction. The outer or free edges or ends of the carrier plates of all the rows lie preferably in close proximity to the inner circumference of the outer fixed drum or casing 3 this casing and the rotary casing 2 with its annular rows of plates being preferably arranged in the vertical position shown.

The upper end of the outer fixed casing or drum 3 is closed by a suitable cover or plate 4 formed with an opening through which the material to be dried is fed by means of a rotary star feeder 5, see Fig. 4, or other appropriate feeding device, for example as

hereinafter described with reference to Figs. 15 to 20 inclusive.

An annular heating chamber 6 around the lower part of the fixed casing or drum 3 is fitted with suitable coils 7 through which steam is passed. Air enters the upper end of the heating chamber 6 and, after passing through the heater in doing which it becomes heated by contact with the steam coils 7, the heated air enters the annular drying chamber in which the carrier plates 1 work between the fixed casing 3 and rotary drum 2 through an opening or openings 8 formed through the wall of the fixed casing 3 near the lower end thereof. A suction fan or the like connected to an air outlet 11 in the cover or plate 4 closing the upper end of the fixed casing or drum draws air through the air heating chamber 6 and upwardly through the annular drying chamber so that it plays upon the material passing through the same on the carrier plates 1 and out through the opening 11 formed in the fixed cover or plate 4, into the suction conduit 12 of the fan or the like.

The lower end of the outer fixed casing or drum 3 terminates in an inverted conical shaped extension 13 the bottom of which is fitted with a discharge device consisting of a wheel 14, fixed on the lower end of the central vertical shaft 15 which carries the rotatable drum 2, the said wheel being formed with radial blades that constitute pockets into which the dried material falls. This bladed wheel 14 works over a flat plate 16 that closes the end of the conical bottom 13 of the fixed casing 3 and a discharge opening 17 is formed in the plate 16 through which the dried material falls as the bladed wheel 14 rotates over the same. To prevent entrance of cold air through the opening 17 into the casing a horizontal plate 17^a fixed to the casing is arranged to extend over the bladed wheel 14 at a point directly over the said opening 17, the arrangement being such that material falling between the blades of the wheel 14 is carried below the fixed plate and drops out through the discharge opening 17 as the wheel continues its rotation.

The vertical shaft 15 is mounted to rotate in bearings 19 at the top and bottom of the fixed casing 3 and the weight of the rotary drum 2 and the parts connected thereto is carried by a ball or roller bearing 20 located above the casing and on which rests a collar 21 fixed to the shaft 15.

It will be understood that the particles of dried material entrained in the heated drying air are thrown by centrifugal force towards the wall of the fixed casing 3 as the hot air is flowing upwardly through the annular drying chamber.

The carrier plates 1 are preferably steam heated for which purpose they may each consist, as shown in Figs. 9, 10 and 11, of a

hollow casting to which steam is admitted, or, as shown in Figs. 12, 13 and 14, of a casting in which is cast a coil 22 of steam pipe, the inlet and outlet ends of which are exposed convenient for connecting thereto a steam supply pipe 23 and a drain 24, see Figs. 7, 8 and 14. A number of steam pipes 23 corresponding to the number of carrier plates 1 in each row thereof, extend vertically within the rotary drum 2 alongside the wall thereof and a similar number of drain pipes 24 also extend vertically alongside the said steam pipes. The steam pipes and the drain pipes are each provided with bent branches 25 and 26 respectively corresponding in number and position to the annular rows of carrier plates and the branches 25 of the steam pipes are suitably connected as by unions 27 to the steam inlets of the carrier plates or trays, the branches 26 of the drain pipes being similarly connected to the outlets of the said carrier plates. The arrangement of these connections can be clearly seen in Figs. 7, 8 and 14. The upper ends 25 of the vertical steam pipes 23 are connected to radial pipes 28 each fitted with a control valve 29, to a hollow steam distributing collar 30 embracing the vertical shaft 15 and rotating therewith, suitable glands 31 at the top and bottom of the collar 30 being installed for the purpose of maintaining a steam tight joint. Radial ports in that part of the shaft embraced by the distributing collar 30 place the interior of the collar and the steam pipes connected thereto in communication with an axial boring 32 extending to the upper end of the shaft. A steam supply pipe 33 is suitably connected, as shown, to the upper end of the vertical shaft 15 so that steam is delivered, through the axial boring 32, and collar 30 to the steam pipes and heating conduits of the carrier plates 1. In like manner the lower ends of the drain pipes 24 are connected through valve controlled radial pipes 34 to an axial boring 35 in the lower part of the vertical shaft 15, the lower end of which shaft is suitably connected, as shown, to a drain pipe 36.

50 In the top cover plate 4 and circumferential wall of the fixed casing 3 appropriately arranged access doors 37 are provided where desired, the access door in the top cover plate 4 giving access to the valves 29 controlling the supply of steam to the vertical steam pipes 23, the spindles of such valves extending through holes formed therefor in the plate 10 closing the upper end of the rotary drum 2, and an access door 38 in the conical extension 13 of the fixed casing giving access to the controlling valves 39 of the drain pipes 24. 40 is a manhole formed in the conical extension of the fixed casing.

55 Motion may be transmitted to the vertical

shaft 15 as by means of a worm and worm wheel 41 driven from any suitable source of power and at a predetermined speed. In the example shown the shaft is driven by an electric motor 42 suitably mounted on a supporting structure arranged above the fixed casing.

60 The feeder or charge device 5 on the top of the fixed casing 3 in the arrangement shown in Figs. 1, 2 and 4, is a device of a known kind adapted to be rotated at a predetermined speed during the working of the apparatus so that the quantity of charge of material adapted to be accommodated on each carrier plate of the first or uppermost 70 annular row will be delivered on to the said plate at the proper time, i. e., when the same is passing below the outlet from the said feeding device. In the apparatus under notice the feeding device 5 is driven from the 75 vertical shaft 15 through bevel gear 43.

75 The devices for spreading the material to be dried over the surface of the carrier plates each consists of a metal arm 44, Figs. 3 and 7, pivoted by a pin 44^a to the wall 90 of the casing 3 and extending inwardly over the carrier plates 1 at such a height above the same as to spread the material in a thin layer thereon as the carrier plates pass below the said arm. These spreading arms are supported at the right height by pins 44^b projecting from the outer casing but they may rise if required in order to avoid damage should a lump of coal or foreign substance become wedged under a spreader. The devices for scraping the material off the carrier plates 1 also each consist of a pivoted metal arm 45, Figs. 3 and 7, upon the lower edge of which the carrier plates rub as they travel under the same. The scrapers are pivoted by pins 45^a to the casing 3 and rest directly upon the plates during the scraping operation, but drop slightly on to supporting pins 45^b fixed to the outer casing as they leave the plates. 95 The metal arms 44 and 45 constituting the mechanical spreaders and scrapers may each be made of a short length of metal bar so bent as to form a part adapted to be pivoted to the wall of the fixed casing and an arm or operative portion that extends at a suitable angle from the said part as shown in Fig. 3.

100 One of the mechanical spreaders 44 is provided at such a position in relation to the inlet for the material from the feeding device 5 that at a suitable interval after the first carrier plate 1 of the first or uppermost annular row (with its heap of fuel or material delivered thereto from the feeding device) has passed clear of the feeding device, its leading edge will come under the spreader which will nicely spread the heap of material over the surface of the carrier plate. A similar spreader is provided for 105 each annular row of carrier plates carried 110

by the rotary drum 2. Similarly the scrapers 45 for removing the layer of more or less dried material from the carrier plates of one annular row to the carrier plates of the next annular row are located in such a position that each carrier plate approaching and coming in contact with the scraper will have the spread and more or less dried material thereon removed from it by the 10 scraper just prior to the carrier plate arriving at the position when the next charge or quantity of material will be delivered thereon in a heap either through the initial feeding device 5 at the top of the apparatus 15 or from a carrier plate of an upper annular row.

The undersides of the carrier plates 1 may be plain as in Figs. 9, 10 and 11 or formed with ribs or ridges 50 in order to increase 20 the heating surface in contact with the hot air, as shown in Figs. 13 and 14.

In the modified arrangement of feeding device shown in Figs. 15, 16 and 17, a series of perforated plates 51 formed it may be of 25 expanded metal, as shown, are substituted for or arranged above the top row of carrier plates 1. The material is fed on to these perforated plates through a feed chute 52, the thickness of the layer deposited 30 thereon being regulated by the adjustment of a regulating plate 53, see Fig. 17. With this arrangement the air as it leaves the annular drying chamber has to pass through the layer of wet material on the perforated 35 plates 51 and such material consequently constitutes a filter for removing the dust from the said air and renders the action of the drying apparatus more satisfactory and complete.

40 The perforated plates 51 are provided near one edge with trunnion pins 54 mounted to rock in an inner metal ring 55 fixed to the rotary drum 2, and an outer metal ring 56 fixed to the said inner ring 55 by a number of radial brackets 57, see Fig. 16. Rollers 59 on the fixed casing 3 support the outer ring 56 as it travels round with the drum 2 and fixed by brackets 60 to the said casing 3 is an angle iron support 61 on which the 45 perforated plates 51 rest. 51^a indicates wearing strips at the free edges of the plates 51. The angle iron support 61 consists of a ring having an interruption at the point where the perforated plates 51 tilt in order to 50 dump the material on to the carrier plates 1 below. From Fig. 17 it can be seen that the perforated plates 51 are supported by the angle iron ring 61 in a horizontal position until the point of interruption is 55 reached when the plates tilt and the material falls off the same. The leading end of the angle iron support 61 is bent downwardly as shown in Fig. 17 so that upon continued movement of the rotary drum the plates 51 60 are caused to ride up the downwardly bent 65

angle iron and assume the desired horizontal position prior to receiving a fresh charge of material from the feed chute 52.

In order to prevent a rush of air through the gap formed at the point where the perforated plates 51 tilt about their trunnions, an air baffle in the form of a bent metal plate 62 is provided over the row of perforated plates at the said point, see Fig. 17.

70 From the foregoing it will be seen that the improved system and apparatus according to this invention will effect the drying of material in a rapid and continuous manner by a number of steam heated carrier plates or trays 1 arranged in sets one below 75 another and with which spreaders 44 and scrapers 45 co-operate for the purposes hereinbefore mentioned, the spreading of the material on the plates or trays 1 ensuring that the moisture in the material shall be 80 thoroughly dried out and this thorough drying being further ensured by the fact that the more or less dried material removed from the plates or trays of one set by the 85 action of the hereinbefore mentioned scraper or scrapers is turned over or redistributed and is thereafter again spread upon the plates or trays of the second or lower set and so on according to the number of sets 90 of plates or trays provided in the apparatus. 95

Modifications might be made in the details of construction and arrangements above set forth without departing from the main features of the invention, for example the heating medium may consist of hot gases 100 of combustion from a furnace or other suitable source.

What I claim is:—

1. In a drying apparatus, a stationary casing for hot air, carrier plates for the material spaced apart and arranged one above another in staggered relation in the casing, means for feeding the material onto the top carrier plates intermittently in predetermined quantities, means for spreading the material on the carrier plates, and means for subsequently scraping the material off the carrier plates so that it descends in the casing by gravity. 105

2. In a drying apparatus, a stationary vertical casing for hot air, a rotary drum mounted in the said casing, carrier plates for the material secured to the rotary drum and spaced apart and arranged one above another in staggered relation in the casing, means for feeding the material onto the top carrier plates intermittently in predetermined quantities, means for spreading the material on the carrier plates, and means for subsequently scraping the material off the carrier plates so that it descends in the casing 110 by gravity. 120

3. A drying apparatus as set forth in claim 2, the said means for spreading the material on the carrier plates comprising 125 130

arms pivoted to the stationary casing and extending over the said plates, and stops which limit the downward movements of the said arms.

5 4. A drying apparatus as set forth in claim 2, the said means for scraping the material off the carrier plates comprising arms pivoted to the stationary casing and adapted to rest on the plates, and stops which limit 10 the downward movements of the said arms when not resting on the plates.

5 5. A drying apparatus as set forth in claim 1, the said carrier plates being provided internally with steam chambers for 15 heating them, pipes for supplying steam to the steam chambers, and pipes for draining the steam chambers of water.

6 6. A drying apparatus as set forth in claim 1, the said carrier plates having externally corrugated undersides which are 20 exposed to the hot air in the stationary casing.

7 7. A drying apparatus as set forth in claim 1, the said stationary casing being provided with an inlet for hot air at its lower 25 part below the carrier plates and an outlet for hot vapor at its top above the carrier plates.

8 8. A drying apparatus as set forth in claim 2, the said stationary casing having a 30 conical lower end portion and a flat discharge plate provided with an outlet opening for dry material, and a discharge device revolving with the said drum and working over the said flat plate and its opening.

9 9. A drying apparatus as set forth in claim 2, the said stationary casing having a 35 conical lower end portion and a flat discharge plate provided with an outlet opening for dry material, and having also a flat plate spaced apart from the discharge plate; and a discharge wheel revolving with the 40 said drum and provided with arms which work between the flat plates and over the 45 said outlet opening.

10 10. A drying apparatus as set forth in claim 2, the said carrier plates being provided internally with steam chambers, a 45 main steam supply pipe mounted concentric with the said drum, a series of vertical steam distributing pipes communicating with the steam chambers of the carrier plates which are directly above one another, radial steam pipes connecting the main steam pipe with 55 the said distributing pipes, and pipes for

draining the said steam chambers of water.

11. A drying apparatus as set forth in claim 2, the said carrier plates being provided internally with steam chambers, a main drain pipe for water mounted concentric with the said drum, a series of vertical drain pipes communicating with the steam chambers of the carrier plates which are directly one above another, radial drain pipes connecting the vertical drain pipes with the 60 said main drain pipe, and pipes for supplying steam to the said steam chambers.

12. A drying apparatus as set forth in claim 2, the said means for feeding the material onto the top carrier plates comprising a series of pivoted perforated plates which support the wet material in the path of the dust at the outlet part of the hot air casing, said perforated plates being arranged to revolve with the said drum and 70 provided with means for tilting them one after another automatically at a predetermined point to discharge the material onto the carrier plates.

13. A drying apparatus as set forth in claim 2, the said means for feeding the material onto the top carrier plates comprising a series of pivoted perforated plates which support the wet material in the path of the dust at the outlet part of the hot 85 air casing, said perforated plates being arranged to revolve with the said drum and provided with means for tilting them one after another automatically at a predetermined point to discharge the material onto 90 the carrier plates, and a stationary baffle plate arranged over the perforated plates at their point of discharge and while they are tilted.

14. A drying apparatus as set forth in claim 2, the said means for feeding the material onto the top carrier plates comprising a series of pivoted perforated plates arranged above the said carrier plates in the stationary casing, means for pivotally supporting the said perforated plates from the said drum, and a stationary annular support for the perforated plates to rest on having a gap arranged at the point of discharge of the perforated plates and permitting them 100 to tilt pivotally one after another and dump the material onto the carrier plates.

In testimony whereof I affix my signature.

FAY HARRY ROSENCRANTS.
